US00D703987S

(12) **United States Design Patent**
Smith et al.

(10) **Patent No.:** **US D703,987 S**
(45) **Date of Patent:** **** May 6, 2014**

(54) **CHAIR**

(71) Applicant: **Steelcase Inc.**, Grand Rapids, MI (US)

(72) Inventors: **Bruce M. Smith**, East Grand Rapids, MI (US); **Nickolaus William Charles Deever**, Holland, MI (US)

(73) Assignee: **Steelcase Inc.**, Grand Rapids, MI (US)

(**) Term: **14 Years**

(21) Appl. No.: **29/457,254**

(22) Filed: **Jun. 7, 2013**

(51) LOC (10) Cl. **06-01**

(52) U.S. Cl.

USPC **D6/716.4**

(58) **Field of Classification Search**

USPC D6/334-336, 364, 365, 366, 367, 374, D6/376, 379, 380, 716, 716.1, 716.2, D6/716.3, 716.4; 297/284.4, 300.1, 300.2, 297/411.27, 452.21, 452.29, 452.3, 452.32, 297/452.34, 452.48, 452.63

(57) **CLAIM**

We claim the ornamental design for a chair, as shown and described.

DESCRIPTION

FIG. 1 is a perspective view of a chair embodying the present invention;

FIG. 2 is a front view of the chair;

FIG. 3 is a first side view of the chair;

FIG. 4 is a rear view of the chair; and,

FIG. 5 is a top view of the chair.

The broken lines shown in the drawing are for illustrative purposes only and form no part of the claimed design.

1 Claim, 1 Drawing Sheet
